UNITED STATES PATENT OFFICE.

MORLEY FUNSHON REYNOLDS, OF CLEVELAND, OHIO, ASSIGNOR TO THE W. S. TYLER COMPANY, OF CLEVELAND, OHIO, A CORPORATION OF OHIO.

SCREENING APPARATUS.

1,423,021.

Specification of Letters Patent.

Patented July 18, 1922.

Application filed September 22, 1919. Serial No. 325,428.

To all whom it may concern:

Be it known that I, MORLEY FUNSHON REYNOLDS, a citizen of the United States, and a resident of Cleveland, county of Cuyahoga, and State of Ohio, have invented a new and useful Improvement in Screening Apparatus, of which the following is a specification, the principle of the invention being herein explained and the best mode in which 10 I have contemplated applying that principle, so as to distinguish it from other inventions.

The present invention, relating, as indicated, to screening apparatus, is particularly directed to means for supporting and reinforcing a woven wire screen or the like in order to increase the resilience, vibratory action and effective life of the screen. It has been found that light woven wire screens 20 of fine wire cannot be given a sufficient movement under vibration to effect a rapid and accurate screening action, except with injury to the screen, due to the very considerable stretching caused on the wires of the screen by the continued vibration, and by 25 the weight of the load passing thereover. While any ordinary amount of stretching is not injurious to the screening action, nevertheless, a light screen, when subjected to severe vibration and then continuously tensioned to maintain a uniform vibratory tension over the surface of the screen, is sometimes stretched to a point beyond the elastic limit of the wire. A stretching beyond 30 this elastic limit draws the wires, causing them to harden and making them liable to breakage, while it entirely destroys the effective vibratory action of the screen. The present invention has been developed to support and reinforce wire screens in order to 35 prevent any undue stretching of the wires and to partially absorb the very severe vibratory impulses, to which these screens must be subjected to secure the proper vibration when working under a heavy load of material. To the accomplishment of the foregoing and related ends, said invention, then, consists of the means hereinafter fully described and particularly pointed out 45 in the claims.

The annexed drawing and the following description set forth in detail certain mechanism embodying the invention, such disclosed means constituting, however, but one

of various mechanical forms in which the principle of the invention may be used.

In said annexed drawings:

Fig. 1 is a plan view of my improved screen mounted upon a frame and partially in section to show the construction; Fig. 2 is 60 a transverse section across the same; and Figs. 3 and 4 are enlarged partial transverse sections illustrating the various means for mounting the screens.

In screening operations a very high tonnage of material is sometimes passed over the screen, and the weight of the material causes a universal stretching of the wires of the screen, which is of course accentuated in some places due to uneven temper of the wire from which the screen is woven. This is particularly true in the case of light screens which do not have the strength and resistance of those of coarser mesh.

My invention consists in providing a series 75 of resilient supporting members for reinforcing the screen, these members being most conveniently provided in the form of a second coarser screen mounted below the fine screen. In Fig. 1 there is shown a frame 80 consisting of movable side members in the form of angle plates 1 freely supported at their ends upon transverse end members 2 and connected by means of tensioning bars 3, having a right and left-hand threaded 85 connection with suitable sockets 4 formed as a part of the bars 1. Removably mounted on the upper surfaces of the angle plates 1 are S-shaped strips of metal 6 which have inturned lower flanges 7 engaging beneath 90 the plates 1 and re-bent upper portions 8 adapted to clamp the inturned edge of the screen 10 against the body of the strip 6. This type of frame construction and screen mounting is that described and claimed in 95 the patent to F. S. Curtis, No. 1,249,087, issued December 4, 1917. It affords a uniform clamping action of all of the transverse wires of the screen and thus prevents the pulling out of any individual wires as 100 was the case when the edges of the screen were tacked, bolted or riveted to the frame.

Mounted beneath the light screen 10 is a second coarser screen 11, having its edges also re-bent for clamping between the re-bent 105 flanges 8 of the strip 6 and the body of the strip. The two screens are supported at the point of clamping by means of strips of

frictionel material 12 and the lower or coarser screen is supported from the re-bent flange 8 by a second similar strip 13, thus enabling the flange on the strip 6 to be 5 clamped down tightly against the inturned edges of the screen without injuring the same, although, at the same time, securing a firm grip on these edges.

If desired, two S-shaped hooks 14 and 15 10 may be used as shown in Fig. 4, in which case the lower strip 15 is wider than the upper and carries the coarser screen 11, which is, however, in substantial contact with the upper screen 10, as is also the case in the mounting shown in Fig. 3. The two screens may 15 be tensioned simultaneously and uniformly by the adjusting bars which act to space the angle plates 1 and thus pull the S-shaped strips away from each other throughout 20 their entire length.

The action of the lower or supporting screen is to reinforce the upper screen against the weight of material passing over it, and at the same time to assist in the 25 vibration of the same, since a better vibration can usually be secured from a coarser wire than from the very fine wires which are used in fine mesh screens. The screening action is not effected by the supporting 30 screen as the meshes of this screen are, of course in every case larger than the meshes of the upper screen, and any material passing through the upper screen will similarly pass through the meshes of the lower screen.

35 Other modes of applying the principle of my invention may be employed instead of the

one explained, change being made as regards the mechanism, herein disclosed, provided the means stated by any of the following claims or the equivalent of such stated means 40 be employed.

I therefore particularly point out and distinctly claim as my invention:—

1. In mechanism of the character described, the combination of spaced pairs of 45 superimposed strips rebent laterally upon themselves throughout their length, woven wire screens mounted upon the corresponding strips of the pairs and having their overlying edge portions clamped beneath such 50 rebent portions of said strips and means engaging said strips for moving the same with respect to each other to tension said two screens equally and together.

2. In mechanism of the character de- 55 scribed, the combination of spaced strips rebent laterally upon themselves throughout their length, said rebent portions being in offset relation, two superimposed woven wire screens having their overlying edge 60 portions clamped beneath such rebent portions of said strips, frictional material interposed between such clamped edge portions of said screens and said screens being of different mesh, the coarser mesh being below the 65 other and means engaging said strips for moving the same with respect to each other to tension both screens simultaneously to fixed uniform predetermined tensions.

Signed by me, this 16th day of Sept., 1919. 70

MORLEY PUNSHON REYNOLDS.
